VACUUM GAUGE

Russell H. Varian, Garden City, N. Y., assignor to
The Sperry Corporation, a corporation of Delaware

Application March 31, 1945, Serial No. 586,006

9 Claims. (Cl. 175—183)

1

The present invention relates to methods and apparatus for measuring very low gas pressures such as are encountered in evacuated electron discharge devices, usually referred to as vacuum tubes.

The principal object of the present invention is to measure the gas pressure within an evacuated space.

It is another object of this invention to provide a method of determining the gas pressure 10 in a vacuum tube.

Another object is to provide an improved vacuum gauge.

It is a further object to provide a vacuum gauge adapted for measuring gas pressures 15 throughout a relatively extensive range such as the range from 10^{-6} to 10^{-10} millimeter of mercury.

In the present invention, electrons are projected along a directive beam through an evacuated space, and the compactness of the electron stream is modulated by the formation of ions therein. The number of ions within the electron beam tends to remain substantially equal to the number of electrons in the beam, and thus does not vary appreciably. This is seen from the fact that when the number of ions within the electrons therein, the net charge of the beam becomes substantially neutral. If the number of ions in the beam tends to exceed the number of electrons at any instant in the beam, the beam tends to have a net positive charge which, by repelling the ions from the beam, increases the rate at which the ions drift from the beam. Thus, the ion content of the beam is self-adjusting to a number of ions just sufficient to neutralize the beam charge. The rate of formation of ions in the electron beam by collision of electrons with gas molecules is approximately proportional to the gas pressure. Accordingly, as the gas pressure is decreased, and the rate of ion formation is correspondingly decreased, each ion must remain effective in the electron beam longer than under higher gas pressure conditions, in order to satisfy the above requirement that the number of ions within the electron beam remain substantially equal to the number of electrons therein.

Under a condition of relatively high gas pressure, then, new ions are produced quite frequently in the electron beam, and the average time span of effectiveness of an ion in the beam is quite short. Under a condition of very low gas pressure, new ions are formed infrequently, and the

time span of effectiveness of an ion in the beam is very long.

If no ions were present within the space through which a beam of electrons is projected, the strong negative charge of the beam would tend to cause dispersion of the electrons. The presence of ions within this space tends to neutralize the negative charge, eliminating the electron-repellent tendencies and permitting a compact electron beam to be produced. The ions disappear from the beam and new ions are continually formed to replace them. Since the formation of a new ion is generally not simultaneous with the cessation of effectiveness of another ion, it will be recognized that the number of ions effective in the beam does not remain exactly uniform, but instead increases momentarily at the instant of each ion formation.

The amount of dispersion of the electrons from 20 an ideally compact electron beam varies appreciably with a reduction or an increase by one ion in the number of ions effective in the electron beam. Accordingly, the compactness of the electron beam is modulated in accordance with the formation of new ions in the beam, the frequency of modulation being varied accordingly as the ion formation is frequent with high gas pressure, or infrequent with low gas pressure.

By providing an electron collector adapted to 30 receive only those electrons which are within a predetermined very short distance from the axis of the electron beam, there is produced an electric current which is modulated in accordance with the compactness modulation of the electron beam. The modulation of this current corresponding to a given gas pressure is not a simple periodic wave, since new ions are not formed in the electron beam at precise, regular intervals. On the other hand, the modulation is characterized by a distribution of energy through a wide range of frequencies with maximum amplitude at a frequency dependent upon the pressure of the gas. Due to inertia of the ions, and to the tendency of all ions in the beam to be repelled when there is excess positive charge, very low-frequency components of the modulation are effectively suppressed. If the gas pressure in the evacuated space is relatively high, the ion variation frequency is high, and thus the frequency of the maximum alternating energy content in the current through the electron collector is relatively high. As the gas pressure is decreased, the frequency of maximum energy output of the collector is similarly decreased.

Thus, by analyzing the electron collector cur-

2

rent in terms of the frequency distribution of energy, the gas pressure in the evacuated space may be ascertained. Since the frequency distribution of energy varies as a predictable function of gas pressure throughout a range extending far beyond the range of gas pressures to which ordinary vacuum gauges are limited, the present invention provides an absolute measurement of pressure in extremely high-vacuum devices.

Apparatus suitable for use in determination of the gas pressure within an evacuated system is illustrated in Fig. 1, while Fig. 2 illustrates the frequency distribution of output noise in the apparatus of Fig. 1 resulting from each of three different gas pressures within the system.

Referring now to Fig. 1, an electron discharge device 11, including a cylindrical metallic chamber 12, an electron gun 13 and an electron collector end 14, is connected as by a tubular conduit 15 in a system which may include a vacuum tube in the process of being evacuated.

The electron gun 13 comprises an insulating gas-tight supporting and enclosing portion such as a cup-shaped glass portion 16, which may be sealed to a tubular metal member 17 connected in turn to one end 36 of the cylindrical chamber 12. Within the glass portion 16 is provided an electron emitter or cathode 18 arranged symmetrically about the axis of the cylindrical chamber 12, and supported by a rigid connection to a stiff terminal wire 19 extending through a seal 21 in the glass portion 16. A second conductor 22 similarly extending through the glass portion 16 may be connected to one end of a heater winding 23 having its opposite end connected to the wire 19. A focusing electrode 24 is connected to cathode 18 and supported in specially positioned relation therewith and arranged to direct electrons emitted by cathode 18 into a concentrated stream or electron beam along the axis of the cylindrical chamber 12, the cross-section of this stream becoming very small at the portion thereof approaching the end 37 of the cylindrical chamber 12.

The electron collector end 14 may include a tubular metal portion 31 connected to the end 37 of the chamber 12, and a cup-shaped glass portion 32 sealed to the tubular portion 31. A collector electrode 33 is supported within the collector end by a further stiff terminal wire 34, sealed as shown at 35 in the glass portion 32.

Each of the disc ends 36 and 37 of the cylindrical chamber 12 is provided with an opening symmetrical about the axis of the cylindrical chamber 12. The opening through the end 36 may be of a diameter substantially equal to or greater than the diameter of cathode 18 for permitting the electron beam produced by the cathode 18 and the focusing electrode 21 to enter the cylindrical chamber 12. The opening through the opposite end 37 of the chamber 12 preferably, but not necessarily, may be made appreciably smaller than the input opening, as illustrated in Fig. 1, so that the relative extent to which the electron beam is directed through the exit opening in the end 37 will depend greatly upon the compactness of the electron beam approaching this opening. If desired, an electron-permeable grid 38, which may comprise a screen of small metal wires or a perforated disc, for example, may be inserted within the opening in the end 36 of the chamber 12, and a similar grid 39 may be inserted within the electron exit opening in the end 37.

A first electric energy source such as a battery 44 is connected through the terminal wires 19 and

22 to the heater winding 23 of the electron gun 13, for heating the cathode 18 to provide electron emission therefrom.

An electron accelerating potential source such as a battery 42 is connected at its negative terminal to the cathode 18 and at its positive terminal to the chamber 12 for accelerating to an appreciable velocity the electrons in the beam issuing from the electron gun 13. The source 42 may provide an accelerating potential of the order of 500 volts between the cathode 18 and the end 36 of the cylindrical chamber 12. The heated cathode for emitting electrons, the focusing electrode 24, and the polarized end 36 of the chamber 12 cooperate to project the beam of electrons through chamber 12 toward the exit opening in the end 37 thereof.

If desired, the cylindrical chamber 12 may be grounded, as illustrated in Fig. 1 at 43.

20 A collector polarizing source such as a battery 44 is provided for maintaining the collector electrode 33 at a relatively small positive potential with respect to the cylindrical chamber 12 and ground, a potential of the order of 25 volts being 25 adequate for this purpose. The negative terminal of the battery 44 is connected to the cylindrical chamber 12 and to ground at a junction 45, and its positive terminal is connected through an impedance such as a resistor 46 to the collector electrode 33.

23 A wave analyzer 47 arranged to provide a measurement of alternating energy at any frequency selected by adjustment of a variable frequency control is coupled at one terminal to the collector electrode 33 of the device 11 by a coupling capacitor 48, the other input terminal of the wave analyzer being connected to junction 45. The wave analyzer 47 may be such an instrument as the General radio wave analyzer, model 736-A. Alternatively, it may be such an instrument as is shown in U. S. Patent 1,994,232, issued March 12, 1945, to O. H. Schuck, Jr., for "Wave analyzer."

26 In the operation of the electron discharge device illustrated in Fig. 1, the cathode 18, which may have a planar or slightly concave electron-emitting surface is heated by the heater electrode 23 and is made to emit electrons, which are attracted toward the electron entrance opening in the wall 36 to the chamber 12. The focusing electrode 24 cooperates with the cathode 18 to produce predetermined voltage gradients in the vicinity of the cathode 18 such that the electrons emitted thereby are projected in a concentrated electron beam or stream along a predetermined axis, which may be the axis of the cylindrical chamber 12.

29 Those electrons in the beam projected through the chamber 12 which are near the axis of the chamber are permitted to pass through the exit opening 37 and to be received by the collector electrode 33. On the other hand, those electrons which are spaced appreciably from the axis of the chamber 12 are arrested by the end wall 37 of the device, and thus are prevented from being received by the collector electrode 33.

32 The electric current which circulates through the cathode 18, the collector electrode 33, the impedance 46, and energy sources or batteries 44 and 42, thus increases or decreases accordingly as the electrons in the beam projected by the electron gun 13 are closely concentrated or scattered in the region near the exit through the wall 37 of the chamber 12.

35 Since as pointed out above, the scattering of the electrons from the axis of the electron beam

is sharply dependent upon the number of positive ions in the beam, and since slight variations in the number of positive ions in the beam occur at a frequency substantially proportional to the gas pressure therein, the frequency distribution of variations in the beam scattering is indicative of the gas pressure within the space through which the electron beam is projected. Accordingly, the variations in the electric current through the collector electrode 33, and thus of the voltage produced across the impedance 46, may be frequency analyzed to determine the gas pressure in the device 11, and thus the gas pressure in the system in which the device 11 is connected by conduit 15.

In Fig. 2 is shown a graph including a family of three curves, each of which represents the distribution of electrical output energy vs. frequency corresponding to a selected pressure of the gas within the device 11. Curve I, representing a relatively poor vacuum, or high gas pressure, has its maximum energy content at a relatively high audio frequency f_1 , and has lower intensity at frequencies above and below f_1 . Curve II, representing a better vacuum, which might be characterized by a gas pressure of the order of 10^{-7} millimeter of mercury, for example, contains maximum energy at an appreciably lower frequency f_2 , again having a wide range of frequency components above and below this value at which the output is appreciably reduced. Curve III illustrates an energy vs. frequency distribution having a peak at an extremely low frequency f_3 , corresponding to an extremely high vacuum, as, for example, a gas pressure of the order of 10^{-9} millimeter of mercury. The frequency of the maximum alternating current energy derived from the electron beam is substantially proportional to the gas pressure.

In the apparatus shown in Fig. 1, the substantially unvarying total electron current in the beam is divided into two parts, the first part being a selected middle or central portion of the electron stream which is permitted to pass through the opening in the end wall 37, and the other part being the outer part of the electron stream, which is arrested by the end wall 37 and thus prevented from reaching the collector electrode 33. With the compactness modulation of the electron beam, the current through the collector electrode 33 increases as the beam compactness increases and decreases as the beam compactness decreases. The electron current produced by the collection of the arrested electrons upon the end wall 37 varies conversely, increasing with a decrease of electron beam compactness and decreasing with an increase of electron beam compactness. It will be readily apparent, therefore, that the electron current due to collection of electrons by the end wall 37 is modulated in equal amplitude and reversed phase with respect to the current through the collector electrode. If desired, therefore, a wave analyzer could be coupled to an impedance inserted in series with the connection of the positive terminal of source 42 to the cylindrical chamber 12. This wave analyzer would yield data corresponding exactly with the data obtained through use of wave analyzer 47 connected as shown. Thus, it is optional whether the frequency distribution of energy due to the compactness modulation of the beam be determined by measuring the electron current through a predetermined middle part of the beam or by measuring the electron current outside this middle part of the beam.

It is not essential to the present invention that the electron discharge device 11 be constructed in the form illustrated in Fig. 1. Various types of vacuum tube structures, such as that of the 5 Klystron or velocity modulation tube illustrated in U. S. Patent 2,242,275 to Russell H. Varian, could be employed as the electron discharge device 11, the conduit 15 then being replaced by the 10 tubular connection through which the tube is connected to a vacuum pump during manufacture. Since many types of vacuum tubes of the 15 above class incorporate electron beam projecting devices as well as electron collector electrodes, such vacuum tubes are inherently suited to be connected in the same manner as the electron discharge device 11 in Fig. 1, so that no auxiliary electron discharge device need be employed for measurement of gas pressure in the Klystron. Certain other types of vacuum tubes, also employing directed electron beams, are adapted to 20 be operated while in the evacuation process, and to give output vs. frequency data indicating their own gas pressures.

25 Since many changes could be made in the above construction and many apparently widely different embodiments of this invention could be made without departing from the scope thereof, it is intended that all matter contained in the above description or shown in the accompanying drawing 30 shall be interpreted as illustrative and not in a limiting sense.

What is claimed is:

1. Gas pressure responsive apparatus comprising: an electron discharge device having a 35 chamber including an electron entrance and an electron exit therein, means for directing a concentrated stream of electrons through said electron entrance toward said electron exit, and a collector electrode positioned beyond said exit for receiving electrons passing therethrough; means including a load impedance connected between said collector electrode and said electron stream directing means for providing a current flow path; and means coupled to said load impedance for determining the variation of amplitude with frequency of alternating components of current through said collector electrode.

2. Apparatus as defined in claim 1, wherein 40 said means including a load impedance for providing a current flow path also includes means for raising the potential of said collector electrode above the potential of said chamber.

3. Apparatus for determining the gas pressure 45 within an evacuated space, comprising means for projecting a beam of electrons through said space, a collector electrode positioned in the path of said electron beam for receiving said electrons, circuit means coupling said collector electrode to said projecting means for conducting current therebetween, and frequency-responsive means coupled to said collector electrode and said beam projecting means for determining the frequency distribution of variations of current in said electrode.

5. Apparatus as defined in claim 3, further including means positioned adjacent said collector electrode and between said projecting means and said collector electrode for arresting electrons which are divergent from said path.

6. High-vacuum gas pressure measuring apparatus comprising means for projecting a beam of electrons through an evacuated space, means for selectively rejecting electrons beyond a central portion of said beam and receiving electrons in said central portion of said beam, and

frequency-selective amplitude-responsive means coupled to said last-named means and said beam projecting means for analyzing the frequency distribution of voltage variations of said electrode to determine the gas pressure in said space.

6. High-vacuum gas pressure measuring apparatus comprising means for projecting a beam of electrons through an evacuated space, means for separately receiving electrons within a central portion of said beam and those electrons in the outer portion of said beam, and frequency-selective amplitude-responsive means coupled to said last-named means and said beam projecting means for analyzing the frequency distribution of voltage variations produced by electrons in one of said portions of said electron beam.

7. The method of determining the gas pressure within an evacuated chamber, comprising projecting a beam of electrons along an axis in said chamber and measuring the alternating energy versus frequency characteristics of the electrons in a predetermined portion of said beam.

8. The method of determining the gas pressure within an evacuated chamber, comprising pro-

jecting a beam of electrons along an axis in said chamber, arresting those electrons which are separated from said axis by more than a predetermined distance, and measuring the frequency distribution of alternating components of variation of the non-arrested electrons.

9. The method of measuring gas pressure within an evacuated space comprising directing a beam of electrons through said space and producing ions therein at a rate determined by the gas pressure in said space, the compactness of said beam being modulated as said ions are produced, and measuring the alternating energy versus frequency characteristics of the electrons in a predetermined portion of said beam.
